ANIMAL CAGE COVER

Charles A. Lee and Frank D. Sorrells, Knoxville, Tenn.,
assignors to Appleton Wire Works Corporation, Apple-
ton, Wis., a corporation of Wisconsin

Filed July 1, 1969, Ser. No. 18,001

Term of patent 14 years

Int. Cl. D30—01

U.S. Cl. D30—1

FIG.1

FIG.2

FIG.3

FIG.4

FIG.5

FIG. 1 is a perspective view of the animal cage cover with an animal cage shown in dotted outline;

FIG. 2 is a side elevational view of the animal cage cover shown in FIG. 1;

FIG. 3 is a top plan view of the animal cage cover shown in FIG. 1;

FIG. 4 is an end elevational view of the animal cage cover shown in FIG. 2, the view being taken of the left end of the cover as shown in FIG. 2; and,

FIG. 5 is a sectional view of the animal cage cover taken along the line 5-5 of the cover as shown in FIG. 3.

The dotted lines in FIG. 1 showing an animal cage are for illustrative purposes only and form no part of the claim.

We claim:

The ornamental design for an animal cage cover, as shown and described.
